COMMINUTED FUEL MIXING AND FEEDING APPARATUS

Walter J. Porteous, Saginaw, Mich.

Application August 24, 1933, Serial No. 686,543
Renewed February 17, 1936

5 Claims. (Cl. 259—44)

This invention relates to an apparatus for feeding comminuted fuel such as powdered coal or the like, combined and properly mixed with air, into a combustion chamber. The principal object, therefore, of my invention is to provide a device that will successfully measure and feed comminuted coal and air into a combustion chamber and in such condition as to assure proper and successful combustion of all gases and fuel inside the combustion chamber.

A further object of my invention is to provide a powdered material and air mixing device that may be easily and quickly adjusted by the operator for feeding any desired amount of the comminuted material relative to the amount of air being used.

A still further object of this invention is to provide a powdered fuel mixing and feeding apparatus that is simple in construction and when once installed, requires little or no attention from the operator or user.

A still further object of my invention is to provide a powdered fuel feeding apparatus that will feed the fuel uniformly at all times, thereby eliminating any possibility of the flooding of the powdered material into a combustion chamber.

A still further object of this invention is to provide a comminuted material mixing and feeding apparatus that is economical in manufacture and durable in use.

These and other objects will be apparent to those skilled in the art.

My invention consists in the construction, arrangement and combination of the various parts of the device, whereby the objects contemplated are attained as hereinafter more fully set forth, pointed out in my claims, and illustrated in the accompanying drawings, in which:

Fig. 1 is a front view of my apparatus ready for use and with sections cut away to more fully illustrate the construction of the same.

Fig. 2 is an enlarged side view of the lower portion of the feeding cone valve used in the apparatus.

Fig. 3 is a side sectional view of the operating gears and manual means for adjusting the amount of powdered material being fed by the device.

Fig. 4 is a side view of the apparatus and illustrates the position of the fan housing relative to the other elements of the apparatus.

The greatest possible efficiency that can be obtained from coal is when the same has been reduced to a powdered condition and combined and properly mixed with the correct proportions of

air. It is apparent that the principal difficulties experienced in the burning of comminuted coal or like as a fuel exists in the difficulty of successfully mixing the fuel and air in order that an intense flame will be obtained without the loss of unconsumed particles.

Another difficulty in feeding powdered coal to combustion chambers is the trouble experienced in attempting to measure and stoke the fuel with uniformity in order that undesirable flooding or arching of the fuel will be eliminated. I have overcome such difficulties as will be appreciated by those familiar with the art.

Referring to the drawings, I have used the numeral 10 to designate a hopper or bin for holding the powdered material to be measured, fed, or mixed with air. This hopper 10 has its bottom extending downwardly in the form of a funnel terminating in a circuit opening 11. The numeral 12 designates a conduit having its top open and its length extending downwardly and to one side of the vertical axis of the device. This conduit 12 passes almost directly below the opening 11 in the bottom of the hopper 10. The numeral 13 designates a funnel member having its upper end communicating with the opening 11 and its lower end communicating with the inside of the conduit 12 at a point intermediate of the two ends of the conduit, as shown in Fig. 1. The numeral 14 designates a fan housing having its inlet port communicating with the inside of the lower end of the conduit 12. The discharge end 15 of this fan housing is designed to be in communication with the inside of a combustion chamber or the like. The numeral 16 designates a centrifugal fan rotatably mounted inside the fan housing 14. The numeral 17 designates a gear housing. The numeral 18 designates the base of the apparatus. The numeral 19 designates a supporting webbing secured to the base 18 and supporting the gear housing 17. The numeral 20 designates a similar supporting webbing on top of the gear housing 17 for supporting the conduit 12 and other elements of the apparatus positioned above the gear housing 17. The numeral 21 designates a vertical shaft having its lower end slidably and rotatably extending into the gear housing 17 and its upper end slidably and rotatably extending into the funnel member 13 and bottom portion of the hopper 10, as shown in Fig. 1.

As this shaft 21 extends vertically through the conduit 12 it is embraced by a stationary sleeve 22 to protect the same from engagement with the powdered material. This sleeve 22 has its lower end extending below the conduit 12 and its upper

50

55

- end terminating just inside the flared portion of the funnel member 13. The numeral 23 designates a feeder cone valve rigidly secured to the top of the shaft 21. This cone member 23 has 5 its upper end extending well into the bottom of the hopper 10 and its lower end terminating inside the funnel portion 13 with its lower marginal edge beveled to conform with the inside angle of the flared portion of the member 13.
- 10 The numeral 24 designates a well in the bottom of the cone 23 and adjacent the shaft 21 for loosely accommodating the upper end of the sleeve 22. This well 24 is of sufficient depth to permit the cone 23 to be substantially lowered or 15 raised without the exposure of the upper marginal rim of the sleeve 22. This construction prevents undesirable powdered material passing into the sleeve 22 and around the encased portion of the shaft 21. The numeral 25 designates 20 an agitating arm rigidly secured to the cone 23 and extending upwardly and outwardly inside the hopper 10. The numeral 26 designates a similar but shorter agitating arm rigidly secured to the cone 23 and positioned at a point substantially below the point where the arm 25 25 is secured to the cone. The numeral 27 designates a plurality of spaced apart fins on the lower portion of the cone 23. These fins 27 extend upwardly and forwardly when the cone 23 is 30 rotated to the right in order to produce an auger effect on the powdered fuel inside the funnel member 13 for forcing the same downwardly past the cone 23 and into the conduit 12. The numeral 28 designates a spool rigidly secured on the shaft 21 and positioned between the conduit 12 and the gear housing 17. The numeral 29 35 designates a boss formed on the top of the housing 17 and at one side of the shaft 21, as shown in Fig. 3.
- 40 The numeral 30 designates a rod threaded into the boss 29 and having pivoted at its top and near the center thereof a link 31. The numeral 32 designates two spaced apart vertical circular plates secured to the forward end of the link 31 45 and positioned at each side of the body of the spool 28, for engagement with the spool 28, as shown in the drawings. The numeral 33 designates a similar set of spaced apart vertical circular plates secured to the rear end of the link 31.
- 50 The numeral 34 designates a boss on the top of the housing 17. The numeral 35 designates a rod threaded into the boss 34 and having rigidly secured to its top a spool member 36 engaged in the well known manner by the vertical plates 55 33. The numeral 37 designates a handle member on top of the spool 36 for facilitating the manual rotation of the spool 36 and rod 35. The numeral 38 designates a wheel rotatably mounted in the gear housing 17 and having the fiber ring gear 39 secured by suitable means to its periphery. This gear wheel 38 has a square pole in its center for slidably engaging and accommodating the rectangular portion 40 of the shaft 21, as shown in Fig. 3. The numeral 41 60 designates a fiber washer embracing the bearing axle 42 of the wheel 38. This fiber washer is positioned between the wheel 38 and the bottom of the gear housing 17 and acts as a bearing support for the horizontal gear wheel 38. The numeral 43 designates an oil tray formed on the center portion of the gear wheel 38. The numeral 44 designates an oil filling opening plug in the top of the housing 17 and directly above the tray 43. Oil over-flowing from the tray 43 65 furnishes sufficient oil for all of the moving parts

inside the housing 17. In order to encourage oil to flow toward the outer inside wall of the housing 17, the bottom of the housing 17 extends outwardly and slightly downwardly from its center point, as shown in Fig. 3.

5

The numeral 45 designates a prime mover mounted on the base 18 and having the drive shaft 46. The numeral 47 designates a shaft having one end operative connected to the drive shaft 46 and its other end operatively connected 10 to the fan 16. The numeral 48 designates a worm gear embracing and rigidly secured on the shaft 47 intermediate of its two ends. This worm gear 48 is positioned inside the gear housing 17 and is in mesh with the fiber ring gear 39 of the 15 gear wheel 38. The numeral 49 designates a mesh screen closing the upper end of the conduit 12.

The practical operation of the device is as follows: With powdered material in the hopper 10 20 and the prime mover 45 running, the member 37 is rotated to the right, thereby moving the outer end of the link 31 downwardly and its inner end upwardly. This movement of the link 31 will cause the vertical shaft 21 to move upwardly 25 carrying with it the feeding cone valve 23. With the cone 23 moved upwardly a space will exist between its lower end portion and the funnel portion 13 and it is through this space that the powdered material passes from the hopper 10 and 30 funnel member 13 downwardly into the conduit 12. Naturally, the space between the lower end of the cone 23 and the funnel member 13 will determine the amount of material being fed into the conduit 12. This space is adjustably had by 35 rotating the control handle member 31 to the right or to the left. The position of the central portion of the link 31 may be obtained for zeroing purposes by rotating the rod 30. The prime mover 45 will rotate the shaft 47 to the right, 40 thereby rotating the worm gear 48 and fan 16. As the fiber ring gear 39 is in engagement with the worm gear 48 the same will be rotated to the left, which will also rotate the shaft 21 to the left and its feeding valve cone 23.

45

As the arms 25 and 26 are secured to the rotating cone 23 they will agitate and break up the material inside the hopper, thereby causing the same to pass readily into the top of the funnel member 13. The fins 27 will engage this powdered 50 material and force it downwardly through the space existing between the cone and funnel member when the cone member is in an elevated operating position. The suction of the fan 16 will also aid in drawing the powdered material downwardly into the conduit and into the fan housing 14. The fan 16 will also draw in air through the top of the conduit 12 and this air and powdered material will be substantially mixed upon its entrance into the fan housing, due to the fact 60 that the powdered material will fall directly into the current of air passing through the conduit 12. Inside the fan housing the proper mixing of the air and powdered material will be completed, due to the action of the fan 16 which will deliver 65 the mixed air and powdered material through the discharge portion 15 of the fan housing and into the combustion chamber.

55

From the foregoing it will readily be seen that I have provided a device for successfully feeding and mixing air and powdered material into a combustion chamber and one that is entirely controlled and regulated by the single handle knob member 37.

70

75

Some changes may be made in the construction and arrangement of my improved comminuted fuel mixing and feeding apparatus without departing from the real spirit and purpose of my invention, and it is my intention to cover by my claims any modified forms of structure or use of mechanical equivalent which may be reasonably included within their scope.

I claim:

- 10 1. In a device of the class described, a fan housing having inlet and outlet ports, a fan rotatably mounted in said housing, a downwardly inclined conduit having its upper end communicating with the outside atmosphere and its lower end communicating with the inlet port of said fan housing, a downwardly extending funnel member designed to be in communication with a source of powdered material and its lower end communicating with the inside top of said conduit at a point between its two ends, an upwardly extending vertical cone feeding valve having a flat bottom and rotatably mounted wholly in said funnel member, a means for adjustably obtaining the vertical position of said valve relative to said funnel member, and a prime mover for rotating said fan and said valve.
- 15 2. In a device of the class described, a fan housing having inlet and outlet ports, a fan rotatably mounted in said housing, a conduit having one end communicating with the outside atmosphere and its other end communicating with the inlet port of said fan housing, a downwardly extending vertical funnel member designed to be in communication with a source of powdered material and its lower end communicating with the inside top of said conduit at a point between its two ends, an upwardly extending vertical cone feeding valve having a flat bottom and wholly rotatably mounted in said funnel member for controlling the amount of material passing through the said funnel member, agitating arms secured to said cone feeding valve, a means for adjustably positioning the height of said valve relative to said funnel member, and a means for rotating said fan and said valve.
- 20 3. In a device of the class described, a fan housing having inlet and outlet ports, a fan rotatably mounted in said housing, a conduit having one end communicating with the outside atmosphere and its other end communicating with the inlet port of said fan housing, a downwardly extending vertical funnel member designed to be in communication with a source of powdered material and its lower end communicating with the inside top of said conduit at a point between its two ends, an upwardly extending vertical cone feeding valve having a flat bottom and wholly rotatably mounted in said funnel member for controlling the amount of material passing through the said funnel member, a means for adjustably positioning the height of said valve relative to said funnel member, and a means for rotating said fan and said valve.
- 25 4. In a device of the class described, a fan housing having inlet and outlet ports, a fan rotatably mounted in said housing, a conduit having one end communicating with the outside atmosphere and its other end communicating with the inlet port of said fan housing, a downwardly extending vertical funnel member designed to be in communication with a source of powdered material and its lower end communicating with the inside top of said conduit at a point between its two ends, an upwardly extending vertical cone feeding valve having a flat bottom and wholly rotatably mounted in said funnel member for controlling the amount of material passing through the said funnel member, a means for adjustably positioning the height of said valve relative to said funnel member, and a means for rotating said fan and said valve.
- 30 5. In a device of the class described, a fan housing having inlet and outlet ports, a fan rotatably mounted in said housing, a conduit having one end communicating with the outside atmosphere and its other end communicating with the inlet port of said fan housing, a downwardly extending vertical funnel member designed to be in communication with a source of powdered material and its lower end communicating with the inside top of said conduit at a point between its two ends, an upwardly extending vertical cone feeding valve having a flat bottom and wholly rotatably mounted in said funnel member for controlling the amount of material passing through the said funnel member, material depressing fins on said cone, a means for adjustably positioning the height of said valve relative to said funnel member, and a means for rotating said fan and said valve.

ber designed to be in communication with a source of powdered material and its lower end communicating with the inside top of said conduit at a point between its two ends, a vertical cone feeding valve wholly rotatably mounted in said funnel member having its lower circular edge smoothly beveled to conform with the inside outline of said funnel member, a means for adjustably positioning the height of said valve relative to said funnel member, and a means for rotating said fan and said valve.

5

4. In a device of the class described, a fan housing having inlet and outlet ports, a fan rotatably mounted in said housing, a conduit having one end communicating with the outside atmosphere and its other end communicating with the inlet port of said fan housing, a downwardly extending vertical funnel member designed to be in communication with a source of powdered material and its lower end communicating with the inside top of said conduit at a point between its two ends, an upwardly extending vertical cone feeding valve having a flat bottom and wholly rotatably mounted in said funnel member for controlling the amount of material passing through the said funnel member, agitating arms secured to said cone feeding valve, a means for adjustably positioning the height of said valve relative to said funnel member, and a means for rotating said fan and said valve.

10

5. In a device of the class described, a fan housing having inlet and outlet ports, a fan rotatably mounted in said housing, a conduit having one end communicating with the outside atmosphere and its other end communicating with the inlet port of said fan housing, a downwardly extending vertical funnel member designed to be in communication with a source of powdered material and its lower end communicating with the inside top of said conduit at a point between its two ends, an upwardly extending vertical cone feeding valve having a flat bottom and wholly rotatably mounted in said funnel member for controlling the amount of material passing through the said funnel member, material depressing fins on said cone, a means for adjustably positioning the height of said valve relative to said funnel member, and a means for rotating said fan and said valve.
